Application February 13, 1939, Serial No. 82,948

Term of patent 7 years

To all whom it may concern:

Be it known that we George C. Holt and Ned D. Fish, citizens of the United States, residing at Fort Madison, in the county of Lee and State of Iowa, have invented a new, original, and ornamental design for a Display Container for Writing Instruments or the like, of which the following is a specification, reference being had to the accompanying drawing forming a part thereof.

Fig. 1 is a perspective view of the display container for writing instruments or the like showing our new design, the container being shown in an opened condition;

Fig. 2 is a top plan view, on an enlarged scale, of the display container of Fig. 1;

Fig. 3 is a front elevational view of Fig. 2; and Fig. 4 is an end elevational view of Fig. 3.

The characterizing feature of the design resides in the display container of the configuration shown having a cover portion disposed upon a base portion, said cover portion having a substantially semi-elliptical shape and said base portion having a stepped cross-section and a contour in the shape of a blunt ended ellipse, as shown.

We claim:

The ornamental design for a display container for writing instruments or the like, substantially as shown and described.
